US0D1054465S

(12) **United States Design Patent** (10) **Patent No.:** **US D1,054,465 S**
(45) **Date of Patent:** **** Dec. 17, 2024**

(54) **LAMINATOR**

(71) Applicant: **Hubei Fangnuo Technology Co., Ltd,**
Wuhan (CN)

(72) Inventor: **Ling Li**, Wuhan (CN)

(73) Assignee: **Hubei Fangnuo Technology Co., Ltd**

(**) Term: **15 Years**

(21) Appl. No.: **29/822,241**

(22) Filed: **Jan. 7, 2022**

(51) **LOC (14) Cl. 15-09**

(52) **U.S. Cl.**

USPC **D15/146**

(58) **Field of Classification Search**

(57) **CLAIM**

The ornamental design for a laminator as shown and described.

DESCRIPTION

FIG. 1 is a Front Perspective view of a laminator showing my new design;

FIG. 2 is a Front view thereof;

FIG. 3 is a Back view thereof;

FIG. 4 is a Left-side view thereof;

FIG. 5 is a Right-side view thereof;

FIG. 6 is a Top view thereof;

FIG. 7 is a Bottom view thereof; and,

FIG. 8 is a Back Perspective view thereof.

The broken lines in the drawings depict portions of the laminator that form no part of the claimed design.

1 Claim, 7 Drawing Sheets
